(57) **CLAIM**

We claim, the ornamental design for a side view type light emitting diode, as shown and described.

DESCRIPTION

FIG. 1 is a perspective view of a side view type light emitting diode, showing our new design;

FIG. 2 is a front elevational view thereof;

FIG. 3 is a rear elevational view thereof wherein the broken lines form no part of the claimed design;

FIG. 4 is a left side elevational view thereof;

FIG. 5 is a right side elevational view thereof;

FIG. 6 is a top plan view thereof; and,

FIG. 7 is a bottom plan view thereof.

UNITED STATES PATENT AND TRADEMARK OFFICE
CERTIFICATE OF CORRECTION

PATENT NO. : Des. 580,378 S
APPLICATION NO. : 29/284227
DATED : November 11, 2008
INVENTOR(S) : Kim et al.

Page 1 of 1

It is certified that error appears in the above-identified patent and that said Letters Patent is hereby corrected as shown below:

Title Page Item (73), Assignee, delete "Anti-electronics Co., Ltd. (KR)" and insert therefor
-- Alti-electronics Co., Ltd (KR) --.

Signed and Sealed this

Sixth Day of April, 2010

David J. Kappos
Director of the United States Patent and Trademark Office
